CLAIM

The ornamental design for an SSD (solid state drive) memory device, as shown and described.

DESCRIPTION

FIG. 1 is a front perspective view of an SSD (solid state drive) memory device;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a rear perspective view thereof;

FIG. 9 is an enlarged view of the encircled portion 9 in FIG. 1;

FIG. 10 is an enlarged view of the encircled portion 10 in FIG. 1; and,

FIG. 11 is an enlarged view of the encircled portion 11 in FIG. 4.

The evenly dashed broken lines in the figures depict environmental subject matter and form no part of the claimed design.

The dot-dash lines encircling enlargement portions of the SSD (solid state drive) memory device form no part of the claimed design.
